United States Patent Office

Des. 196,360
Patented Sept. 24, 1963

196,360

GARAGE DOOR OR SIMILAR ARTICLE

Robert A. Hackathorn, Grosse Pointe Shores, and Richard M. Lytle, East Detroit, Mich., assignors to Crawford Door Company, Detroit, Mich., a corporation of Michigan

Filed Aug. 15, 1961, Ser. No. 66,360

Term of patent 14 years

(Cl. D13—1)

FIG. 1

FIG. 2

FIG. 3FIG. 5 FIG. 6FIGURE 1 is a front elevational view of a garage door, or similar article, showing our new design,

FIGURE 2 is a rear elevational view thereof,

FIGURE 3 is a front elevational view of a modified form of the door shown in FIGURE 1,

FIGURE 4 is a fragmentary perspective view taken from the left of the center panels of FIGURES 1 and 3,

FIGURE 5 is a fragmentary perspective view taken on line V—V of FIGURES 1 and 3; and

FIGURE 6 is a cross sectional view taken on the line VI—VI of FIGURES 1 and 3.

The rear of the door of FIG. 3 is the same as the rear of the door of FIG. 1 which is shown in FIG. 2.

We claim:

The ornamental design for a garage door or similar article, substantially as shown and described.
